UNITED STATES PATENT OFFICE.

OTTO GRAETZER, OF BERLIN-LICHTERFELDE, GERMANY.

THERMOTELPHONE.

1,180,917.

Specification of Letters Patent.

Patented Apr. 25, 1916.

Application filed March 20, 1915. Serial No. 15,900.

To all whom it may concern:

Be it known that I, OTTO GRAETZER, a citizen of the German Empire, and residing at Berlin-Lichterfelde, Germany, have invented certain new and useful Improvements in Thermotelephones, of which the following is a specification.

The present invention relates to thermo-telephones of such kind in which a heating body is formed by arranging one or more Wollaston wires in a block of insulating material which block allows not only the treatment of the very thin Wollaston wires, the so-called heating-conductors, but which serves at the same time as support for these heating-conductors in the telephone-apparatus. Although many constructions for such heating bodies are known the manufacture is still a very difficult one, especially if a great number of heating conductors is to be arranged in the same insulating block.

The object of this invention is to avoid such difficulties by providing an insulating block having an improved structure, where-
25 by the Wollaston wires need not be mounted thereon until the block is finished, but can be placed in position on the finished block at any convenient time. The improved block has a large hole in the center and a number
30 of small holes near the border and a num-
ber of Wollaston wires is introduced in the center-hole and then distributed ray-like to the small holes at the border of the insulat-
35 ing block. When the latter has a circular
shape then all wires or conductors have the same length and the same resistance be-
tween the center hole and the holes at the border of the block.

One embodiment of the invention is re-
40 presented by way of example in the accom-
panying drawings, wherein:—

Figure 1 is a vertical section and Fig. 2
is an elevation of the new heating-body for
thermo-telephones.

45 1 is an insulating-block of any insulating material offering resistance against any influence of acids. Such blocks are prepared by casting, pressing, punching or turning and have preferably such a shape
50 that on the lower side an even surface is formed, whereas the upper side has an indentation 3 surrounded by a higher border 2. This insulating-block is provided with a central hole 4 surrounded by a border 5, which however is not so high as the outer border 2. In this outer border is arranged
55 a number of small holes 6, evenly distrib-
uted over the whole circumference. These
holes 4 and 6 may be produced when manu-
facturing the block itself, *e. g.* during the
casting process, they may however also be
provided later on, *e. g.* by boring. The
heating-conductors are prepared, as known
by means of Wollaston wires, which, in the
suitable number and twisted together into a
rope or bunch 7, are drawn through the cen-
tral hole 4 of the insulating block. By ar-
ranging a knot 8 at the end of this bunch
or by providing any other resistance, a
withdrawal of the bunch is prevented. 70
When using a knot, a loosening of same may
be prevented by putting on a drop of liquid
solder. The upper end of the bunch, pro-
jecting from the hole 4, is untwisted and the
single wires 9 are distributed in such a way
that they may be conducted to and intro-
duced in the holes 6 of the border 2. All
wires have then a radial or ray-like position
in the heating-body. The ends 9' of the
wires, protruding from the lower surface of
the insulating-block are bent outwardly.
Before further treatment this heating body
is provided with a metal-ring 10, the lower
end of which projects over the lower sur-
face of the block so that the lower ends 9'
of all wires come in direct contact with the
inner surface of the metal-ring 10. Then
the lower end of this ring 10 is dipped into
liquid solder and so all wires are secured
or soldered in a very simple manner to the
ring. On the upper side the insulating-
block may for a short time be subjected to a
heating flame, so that by partly melting the
insulating material all small holes will be
closed. An entrance of acid, which later on
is used, is thereby obviated. In order to
avoid also an influence of the acid on the
wires in the central hole, a drop of liquid
insulating-material may be put on the cen-
tral border 5 and on the central part of the
bunch. Also the metal-ring 10 may be cov-
ered with a varnish, able to offer resistance
against acid but preferably dissolvable in
alcohol. After preparing the heating-body
in this way the upper side of the same may
simply be dipped into a suitable acid in or-
der to dissolve the outer silver-cover of the
Wollaston wires, whereas the inner very
thin platinum-wire remains as the heating-
conductor. Instead of dissolving the silver-
cover of the wire, the same may be removed
by an electrolytic process, as known in the
105
110

art. In every case the removal of the silver-cover can take place only at those parts of the Wollaston wires which lie free viz., which are not protected by the material of 5 the insulating-block. These are in general the parts between the central hole 4 and the outer holes 6. After finishing the treatment of the Wollaston wires the whole heating-body is dipped into alcohol in order to 10 remove the varnish, which formerly was arranged on the metal-ring for protection against the acid. Now the heating body is finished and may directly be used in a thermo-telephone in the known manner.

15 By arranging the central border 5 on a lower level than the outer border 2 all the very thin platinum-wires 9, acting as heating-conductors, lie in a plane below the surface of the border 2 and therefore all wires 20 are protected against damage. The length and also the electric resistance of all heating-conductors is quite the same. The number of heating conductors in the heating body may easily be varied as of course a smaller 25 number of wires may be used than holes 6 are provided.

The whole manufacture of the heating-body and the treatment of the Wollaston-wires is very simple and a deterioration of 30 the heating-conductors is impossible. In the finished heating-body the metal-ring 10 forms the one pole and the knot 8 or another resistance in the center of the insulating-block forms the other pole for the electric 35 circuit.

I claim:—

1. In a heating-body for thermo-telephones the combination of an insulating block having a central hole extending 40 through the whole depth of said block and a number of holes near the periphery with a number of Wollaston wires, introduced in the central-hole and ray-like distributed to

the outer holes and a contact-piece on the insulating block connected with the outer 4 ends of the wires.

2. In a heating body for thermo-telephones the combination of an insulating-block of circular shape having a central hole extending through the whole depth of said 50 block and a number of holes near the periphery with a number of Wollaston wires, introduced in the central hole and ray-like distributed to the outer holes and a contact-piece on the insulating block connected with 55 the outer ends of the wires.

3. In a heating body for thermo-telephones the combination of an insulating-block having a central hole surrounded by a border and a number of holes arranged in 60 a border at the periphery of the block, the outer border being higher than the central border, with a number of Wollaston wires, introduced in the central hole and ray-like distributed to the outer holes and a contact-piece on the insulating block connected with 65 the outer ends of the wires.

4. In a heating-body for thermo-telephones the combination of an insulating block having a central hole and a number 70 of holes near the periphery with a number of Wollaston wires, introduced in the central hole and ray-like distributed to the outer holes and a metal-ring arranged at the periphery of the insulating-block, said 75 metal-ring projecting below the lower surface of the insulating-block and the lower part of this ring being in direct contact with the lower and outer ends of the Wollaston wires.

In testimony whereof I affix my signature 80 in presence of two witnesses.

OTTO GRAETZER.
